2 Sheets-Sheet 2

Fig. 2

UNITED STATES PATENT OFFICE.

STANLEY ROBICZEK, OF NEW YORK, N. Y., ASSIGNOR TO THE McCALL COMPANY, OF NEW YORK, N. Y., A CORPORATION OF NEW YORK.

GARMENT PATTERN.

Application filed January 3, 1923. Serial No. 610,409.

This invention relates to garment patterns and particularly to a type of pattern adapted to be used as a guide in constructing garments of continuous tubular fabric such as knitted jersey, tricotette and similar materials.

My improved pattern is distinguished from other types of patterns in that it does not of necessity require a multiplicity of 10 separate pattern pieces to guide the user in making the garment. In fact, generally, a single sheet is all that is necessary. Other points of distinction are referred to hereinafter.

18 The accompanying drawings illustrate two embodiments of the invention, Fig. 1 being a pattern for a dress and Fig. 2 a pattern for a blouse.

Tubular material, for which the present 20 patterns are particularly intended, comes in standard widths, generally 52, 54 or 56 inches; which means that when the material is laid flat the double thickness will be one-half this width. I avail myself of the 25 peculiarities of this material to make a very simple pattern for garments thereof. Each garment, or the main or body portion thereof, when made of this material is in a single piece and I can use a pattern sheet which is 30 of the width of the double material, either before or after taking certain tucks, and can use such a pattern sheet to show where and how the material is to be cut and tucked or otherwise ornamented to get the desired 35 shape, and also to show how the neck, shoulders, arm holes and the like are to be formed. By using the McCall printed pattern system I can show the above points very clearly and in addition can provide printed 40 directions in any desired way such as by diagrams and verbal instructions which will direct the user in performing the successive operations.

In another application for patent Ser. No. 45 609,578, filed Dec. 29, 1922, which I have copending herewith, I have described a particular sort of garment which can be made of tubular material, characterized principally by the provision of certain longitudinally extending tucks which shape the garment and also use the surplus width for ornamentation and for grading according

to the size of the wearer. The patterns of the present invention are designed particularly, though not exclusively, for garments 55 of that sort.

Referring to Fig. 1, the pattern consists of a sheet 10, the width of which corresponds to the width of the tubular material after the tucks have been allowed for (taken up). 60 For example, if 54 inch tubular material is used, this will be a double thickness of goods 27 inches wide and if two tucks of two inches in width are called for on the pattern, its width will be 23 inches. The length of the pattern sheet need not be the full length of the garment as this dimension can be easily determined by the user. However for convenience the length will usually be printed somewhere on the pattern for guidance of 65 the user.

The pattern has printed thereon various reference lines to aid in forming tucks of proper dimensions and to indicate the various points at which the material is to be cut. 75

The lines 12 and 14 are delineated on the pattern to show the width and location of a front tuck on the completed garment, and a line 16 is printed to show the location of the inner edge of the back tuck on the completed garment. A curved line 18 provides a guide for marking the material so that it can be cut away to form the neck line. A reference line 20 indicates the center line of the pattern and reference dots 22 and 24 80 indicate the distances to which the tubular material must be cut or slashed down to provide openings for the arm holes. Darts 26 and 28 are formed in the upper edge of the pattern to show the length of the shoulder seams. The shoulder seams on the garment will correspond respectively to the distances between the points 26 and 30, and the points 28 and 32. 85 90

The pattern also contains a printed chart 95 showing full directions for making up a garment of tubular material. This chart comprises a series of diagrams showing in sequence different steps or operations involved in the making. A set of instructions is also 100 printed and these instructions are expressed in the form of concise statements which are identified with the diagrams. For example the diagrams as shown on the pattern are

numbered from 1 to 7 inclusive, and the directions consist of 7 brief directions which are also numbered from 1 to 7.

Diagram 1 shows a piece of tubular material and instruction 1 states that the material is a 54 inch piece of tubing with the right side out, 52 inches long.

Diagram 2 shows in dotted lines tucks 34 and 36 which are to be stitched down 10 each side of the material from the folded edge, and instruction 2 expresses this idea in a brief yet concise way.

The next step in making the garment is to shift the material so that the stitching 15 of the front tuck will be, say for example, 8½ inches from the left side and the stitching of the back tuck will be 8½ inches from the right side.

Diagram 3 shows the tucks 34 and 36 thus 20 shifted and instruction 3 explains the step. The next step is to slash down or cut the material the required distance from the upper edge to form the arm hole. For the garment shown in the pattern illustrated, 25 this distance is 7½ inches. This step is illustrated in Diagram 4 and is explained in instruction 4.

The fifth step is to cut away the front 30 neck using line 18 of the pattern as a guide and then sewing the upper edges of the tubing together between the points corresponding with 26 and 30 and 28 and 32 on the pattern in order to form the shoulder seams. This step is shown in Diagram 5 and explained in instruction 5. The sleeves are 35 next sewed to the edges adjacent the arm holes with the edges meeting at the shoulder seams. These sleeves are each made of a simple rectangular piece of material and 40 do not require any separate pattern for their cutting. One sleeve is indicated in Diagram 6 and the directions for assembling it is given in instruction 6.

Diagram 7 depicts a front and rear view 45 of the finished garment and the legend 7 so states. Diagram 7 and instruction 7 may be omitted from the pattern if desired or it may be printed on the pattern envelope if desired. The construction diagram and 50 instructions are shown printed on the pattern which is preferable, but it is to be understood that if desired I can print these parts on a separate sheet or on the pattern envelope if desired.

For grading the patterns, that is, making 55 patterns of the same design for persons of different sizes, changes will be made in the width of the pattern sheet, the width or curve of the neck line 18, the location of the points 22, 24, which regulate the size of the arm hole and the width of the tucks. It will be assumed that all sizes of garments are made from the same width of material, say 54 inches, and this fact will generally be 60 printed on the pattern. The grading in

width will then be secured by simply changing the width of the tucks.

In adapting the pattern to different sizes the printed material, of course, will be changed in the dimensions given, as far as 70 may be necessary. The diagrams and printed directions will not have to be changed except in the features referred to.

For a complete dress such as is shown in Fig. 1 it is only necessary to make the pattern correspond to the upper part, the lower part being a mere continuation thereof in a straight tucked tube, and being obvious from the diagram (No. 7). If there were 75 any peculiarities in the lower part of the 80 dress the pattern could be made long enough to show them or separate sheets might be used for accessory parts of the garment.

The pattern of Fig. 1 has its width equal 85 to that of the doubled material after the taking of the tucks illustrated. For some garments it is preferable to make the pattern of the width of the doubled material before the taking of such tucks. An example of this is shown in Fig. 2, which is a pattern 90 for a blouse showing a diagonal tuck 33 extending across the front and back, from the shoulder to the waist. Such a blouse is shown pictorially in the lower part of the figure at 34. In this case the pattern sheet 95 should be of the full length of the garment because the oblique tuck necessitates an offset 35 in the upper edge and another 36 in the lower edge of the material. The printed directions on this pattern are similar in character to those of Fig. 1 and do not need explanation in detail.

The invention is applicable in various ways, thus in Fig. 1 I have shown a pattern 105 sheet itself of desired width and length. In Fig. 2, however, the dimensions are shown in a tinted field surrounded by a margin 37 which is to be cut away in using the pattern.

Attention may be directed to the instructions and lines to be used. In forming the lower edge of the blouse, the front lower edge 38 is convex, or lower at the center and is indicated by the heavy edge of the tinted field. The back lower edge 39 is concave, or shorter in the center and is indicated by a fine line within the tinted field. The printed directions show that both these edges are to be gathered. Directions are also provided for slashing the lower edge at opposite sides to form openings. The center line is offset at the diagonal tuck; the two parts thereof coinciding of course after the tucks have been taken. A seam allowance is indicated at the top and bottom only, remembering that there are no seams at the sides.

While I have described quite specifically a pattern having certain detailed instructions thereon, it is to be understood that the description and the details delineated are to 130

be construed in an illustrative rather than a limiting sense.

What I claim is:

1. A pattern for guidance in making a garment of tubular material comprising a substantially rectangular single pattern sheet the width of which is substantially equal to that of the tubular material, said pattern sheet having indicia thereon for guidance in 10 cutting said tubular material.

2. A pattern for guidance in making a garment of tubular material comprising a single sheet having substantially parallel sides adapted to be aligned with the edges 15 of the tubular material, said pattern sheet

having markings thereon showing the width and location of certain vertically extending tucks.

3. A pattern for guidance in making a complete garment of tubular material comprising a single sheet having substantially parallel sides, the top of said sheet being substantially perpendicular to said sides, said sheet having marks thereon indicating where the material is to be cut to form the neck 20 opening and armholes.

In witness whereof, I have hereunto signed my name.

STANLEY ROBICZEK.
